BUFFING, POLISHING, AND ABRADING DEVICE

Paul Borg, New York, N. Y.

Application April 15, 1947, Serial No. 741,542

5 Claims. (Cl. 51—192)

1

This invention relates to buffing, polishing and abrading devices.

An object of this invention is a portable head for buffing, polishing and abrading devices of such structure that the buffing, polishing or abrading medium may be either supported in such manner as to present a flexible work-engaging face adapted to accommodate itself to surfaces other than flat or may be reinforced to maintain a rigid work-engaging face of predetermined shape.

A further object of this invention is a motor-driven portable buffing, polishing or abrading device which is simple in structure, may be manufactured economically and is highly efficient in operation.

Other objects, novel features and advantages of this invention will become apparent from the following specification and accompanying drawings, wherein:

Fig. 1 is an elevation partly in section of an embodiment of the invention;

Fig. 2 is a fragmentary rear view of Fig. 1;

Fig. 3 is a sectional view partially in elevation illustrating a modification;

Figs. 4 and 5 are illustrations of details, and

Fig. 6 is a fragmentary view generally similar to Fig. 3 illustrating an arrangement of parts different from that of Fig. 3.

A tubular handle 10 supports a yoke 11 at one end. A motor 12 is pivotally supported between the arms of the yoke 11 and is provided with a recess 13 in alignment with the motor axis and with a recess 14 perpendicular to the motor axis. A spring-biased detent 15 is slidably supported by the yoke 11 and handle 10 with a portion projecting through a slot 16 in the handle 10 by means of which the detent may be retracted. With the detent 15 projecting into the recess 14, the motor axis is at right angles to the handle axis but with the detent 15 projecting into the recess 13, the motor axis is in alignment with the handle. A switch 17 is carried by the handle 10 and a flexible conductor 18 connects the motor to the switch while a flexible conductor 19 leads from the switch 17 to a suitable electrical fixture 20, by means of which electrical power may be supplied from a suitable source to the motor 12 through the switch 17.

A hub 21 of any suitable material is fixed to the shaft 22 of the motor 12 by a set screw 23. A metal disk 24 is attached to the face of the hub 21 adjacent the motor by screws or bolts 25. The diameter of the disk 24 exceeds the diameter

2

of the inner end of the hub 21 and the disk constitutes a flange for the hub.

The hub 21 is formed with a concave peripheral surface 26 which is enclosed by a pneumatic annulus 27 equipped with an ordinary tire valve 28 extending through the disk 24 by means of which the annulus 27 may be inflated by use of the pump 29 which, when not in use, is stored in the handle 10. A cover 29 of any material suitable for buffing, polishing or abrading encloses the annulus 27 and hub 21, the cover being formed with an aperture provided at its periphery with a rigid ring 30 interposed between the disk 24 and the annulus 27. The curvature of the surface 26 is such that upon inflation of the annulus 27, the annulus tends first to bind the ring 30 against the disk 24 and then to expand into contact with the cover 29 as shown in Fig. 1. The dimensions of the annulus 27 are such that when inflated, the cover 29 is spaced from the outer end of the hub 21.

In the modification shown in Figs. 3 to 6 inclusive, a circular plate 31 engages the outer face of the hub 21 and is attached to the hub by a bolt or stud 32 extending into a tapped aperture 33 in the hub. The circular plate 31 is of greater diameter than the outer end of the hub so that in effect it constitutes a flange for the hub overlying the pneumatic annulus 27. The plate 31 is formed with a flat face 34 and a convex face 35 either of which may face the cover 29 as shown in Figs. 4 and 6. The plate 31 is provided with a central aperture 36 of the proper diameter to receive the bolt or stud 32 and slots 37 are provided in each face of the plate extending radially from the aperture 36. The stud 32 is provided with radial pins 38 of proper size to be received in the slots 37. By means of the arrangement just described, the plate 31 may be attached to the hub 21 either as shown in Fig. 3 or as shown in Fig. 6 and present a smooth surface to the cover 29.

The device may be utilized either with the motor axis at right angles to the handle axis as shown in the drawings or with the motor axis parallel to the handle axis. Also, the device may be used with the cover 29 supported solely by the annulus 27 with the cover 29 maintained out of contact with any solid surfaces and free to accommodate itself to the contour of the surface to which it is applied. With the plate 31 attached to the hub 21, a backing surface is provided for the cover over the central portion thereof. This surface may be either flat or convex according to the way the plate 31 is attached to the hub

21. With the annulus 27 deflated, the cover 29 is slipped over the annulus to locate the ring 30 adjacent the disk 24. Then, by use of the pump 28, the annulus is inflated, thereby forcing the ring 30 against the disk 24 and expanding it into contact with the cover 29 to support the latter for rotation with the hub 21. Removal of the cover is effected by deflating the annulus 27, thereby providing clearance between the annulus and the periphery of the cover aperture.

The hub 21 provides the peripheral surface 26 having the radial flange 24, and the pneumatic annulus 27 has its inside periphery engaging this surface 26 with what is illustrated as its right hand side wall adjacent the flange 24. The cover 29 fits over the annulus 27 and has a closed end, illustrated as the left hand end, radially stretched tautly by inflation of the annulus 27, and an open end, toward the flange 24, peripherally provided with the ring 30 that can be fitted over the annulus 27 when the latter is deflated, but which is of smaller diameter than the outside diameter of the annulus 27 when the latter is inflated. This ring 30 fits between the right hand side wall of the annulus 27 and the flange 24, the latter having a diameter larger than that of the ring 30, and the peripheral surface 26 flares away from the flange 24. This flaring away of the surface 26 from the flange 24 is very clearly illustrated by the drawings and is the nature of the curvature previously described as causing the annulus to bind the ring against the flange 24. That is to say, with the smaller diameter of the surface 26 toward the flange 24 and the larger diameter away therefrom, inflation of the annulus 27 causes its right hand side wall to grip the ring 30 between it and the flange 24 so as to permit the closed or left hand end of the cover 29 to be radially stretched tautly by the fully inflated annulus.

I claim:

1. A device of the character described comprising a hub having a concave peripheral surface terminating at one end of the hub in a flange perpendicular to the hub axis, a pneumatic annulus surrounding said hub and fitting said concave peripheral surface, a disk attached to the opposite end of said hub in overlapping relation to said annulus and a cover enclosing said disk and said annulus, said cover being formed with an aperture provided at its periphery with a rigid ring interposed between said annulus and said flange.

2. A device according to claim 1 characterized by said disk having a flat surface facing said cover.

3. A device according to claim 1 characterized by said disk having a convex surface facing said cover.

4. A device of the character described comprising a hub having a concave peripheral surface terminating at one end of the hub in a flange perpendicular to the hub axis, a pneumatic annulus surrounding said hub and fitting said concave peripheral surface, a disk at the opposite end of said hub in overlapping relation to said annulus, said disk having one surface flat and the other surface convex, means for attaching said disk to said hub with either surface engaging said hub and a cover enclosing said disk and said annulus, said cover being formed with an aperture provided at its periphery with a rigid ring interposed between said annulus and said flange.

5. A rotary element providing a peripheral surface having a radial flange, a pneumatic annulus having an inside periphery engaging said surface and a side wall adjacent said flange, and a cover fitting over said annulus, said cover having a closed end opposite said flange, with said end radially stretched tautly by inflation of said annulus, and an open end toward said flange and peripherally provided with a ring that can be fitted over said annulus when the latter is deflated but which is of smaller diameter than the outside diameter of said annulus when the latter is inflated, said ring fitting between said side wall of said annulus and said flange, the latter having a diameter larger than that of said ring, and said peripheral surface flaring away from said flange so that inflation of said annulus causes its said side wall to grip said ring between it and said flange and permit said closed end of said cover to be radially stretched tautly by said inflated annulus.
